UNITED STATES PATENT OFFICE.

LEON SOULLIERE, OF DETROIT, MICHIGAN, ASSIGNOR OF ONE-HALF TO FRED A. RAUBOLT, OF WYANDOTTE, MICHIGAN.

LOCK CIRCUIT-CLOSER.

1,171,756.

Specification of Letters Patent. Patented Feb. 15, 1916.

Application filed February 11, 1915. Serial No. 7,576.

To all whom it may concern:

Be it known that I, LEON SOULLIERE, a citizen of the United States of America, residing at Detroit, in the county of Wayne 5 and State of Michigan, have invented certain new and useful Improvements in Lock Circuit-Closers, of which the following is a specification, reference being had therein to the accompanying drawings.

10 This invention relates to a lock circuit closer, and more particularly to a circuit closer which can be advantageously used in connection with an alarm and the ignition system of an automobile to prevent the same 15 from being surreptitiously used or stolen.

As an instance of the use of the device, my invention aims to provide a lock circuit closer that includes a key-actuated switch in conjunction with the ignition system of an 20 automobile, whereby the ignition circuit can be positively broken and secured against completion and another circuit in connection with an alarm established in an open condition, which is closed to sound the alarm 25 should the ignition circuit be tampered with preparatory to starting the automobile.

My invention will be understood from the following description, in connection with the drawings, wherein—

30 Figure 1 is a cross sectional view of the lock circuit closer as connected to the control board or dash board of an automobile; Fig. 2 is an enlarged elevation of the circuit closer, showing the lid broken away to illustrate the key-actuated switch of the ignition and alarm circuits, and Fig. 3 is a diagrammatic view illustrating the electrical connection of the ignition and alarm circuit.

As illustrating an installation of the lock 40 circuit closer, 1 denotes the control or dash board of an automobile and connected thereto by bolts 2, nuts 3 or other fastening means is the rear wall or bottom 4 of a casing 5. This casing has a lid 6 hinged or otherwise 45 connected thereto, as at 7 and the lid is retained in a closed position by a conventional form of lock 8. The lid 6 has another key actuated lock 9 and the bolt 10 of this lock is adapted to engage a resilient contact arm 50 11 carried by and insulated from the upper wall 12 of the casing. The resilient contact arm 11 is connected by a wire 13 to a conventional form of push button switch consisting of buttons 14 and 15 movable in open-

ings provided therefor in the lid 6. The 55 push button switch is adapted to establish a circuit through the medium of a wire 16 with one or more battery cells 17 in the casing 5 and with an ignition device, as a magneto or induction coil 18 of the ignition system of an automobile.

By reference to Fig. 3, it will be observed that the ignition device is connected by a wire 19 to the spark plugs 20 of an internal combustion engine 21 and said engine is connected by a wire 22 to a contact arm 23 carried by and insulated from the top wall 12 of the casing 5. Above the resilient contact arm 11 is a contact piece 24 adapted to be engaged by said arm when the bolt 10 of the 70 lock 9 is extended, and said contact piece is connected by a wire 25 to an audible signal, as an electric bell 26 located within the casing 5. The electric bell 26 is connected by a wire 27 to the wire 16 whereby the battery 75 17 will be included in its circuit.

By again referring to Fig. 3, showing the bolt 10 of the lock 9 in a retracted position, it will be observed that the resilient contact arm 11 engages the contact arm 13 and thereby establishes an open circuit in connection with the ignition system, which can be closed by pushing upon the button 15. This ignition system circuit has been illustrated as closed for establishing the circuit through 85 the spark plugs 20 of the internal combustion engine. When the push button 14 is pressed the spark plug circuit is broken and assuming now that the automobile is to be left standing during the absence of the 90 owner, the operator or owner inserts the key in the lock 9 and extends the bolt 10, thereby placing the resilient contact arm 11 in engagement with the contact piece 24. An open alarm circuit is thereby established and 95 should a person tamper with the push button switch with the expectation of completing an ignition system circuit, pressure upon the push button 15 completes the alarm circuit and sounds the electric bell 26. This notifies pedestrians or others that unauthorized persons are attempting to use the automobile, and it is thought that such alarm will be sufficient to prevent the use of the automobile or any damage thereto.

100

What I claim is:—

A circuit closer comprising a lock having a key actuated bolt normally protruding

from the top of the lock, a contact arm extending over said lock in proximity to the bolt and in a plane below the upper end of said bolt, a resilient contact arm extending 5 on to the end of said bolt and on to said contact arm and adapted to form part of an electric circuit, and a contact piece above the first mentioned contact arm adapted to be engaged by said resilient contact arm when

raised by said bolt to establish a circuit in- 10 dependent of the first contact arm.

In testimony whereof I affix my signature in presence of two witnesses.

LEON SOULLIERE.
